UNITED STATES PATENT OFFICE.

JOSEPH C. FORD, OF MADISON, WISCONSIN, ASSIGNOR TO FRENCH BATTERY & CARBON CO., OF MADISON, WISCONSIN, A CORPORATION OF WISCONSIN.

POCKET HAND-LAMP.

1,257,596.

Specification of Letters Patent. Patented Feb. 26, 1918.

Application filed May 17, 1917. Serial No. 169,365.

To all whom it may concern:

Be it known that I, JOSEPH C. FORD, a citizen of the United States, residing at Madison, in the county of Dane and State 5 of Wisconsin, have invented a certain new and useful Improvement in Pocket Hand-Lamps, of which the following is a specification.

This invention relates to pocket hand 10 lamps of the type commonly known as flash lamps, comprising broadly a case, an electric light bulb, and a dry battery, so combined that the electric bulb is lighted by a current supplied by the dry battery.

15 The object of this invention is to provide a switch for connecting the battery and the electric bulb, located substantially between the two, thereby reducing the number of parts required, and simplifying those which 20 are used, thus doing away with the danger of short-circuiting, resulting in electrical injury to the battery and lamp, and also doing away with some of the mechanical injuries which result with other types of devices if 25 the lamp as a whole is suddenly jarred by dropping or otherwise.

The invention consists in a device capable 30 of carrying out the foregoing objects; which can be very easily and cheaply made; which is satisfactory in operation, and is not readily liable to get out of order. The invention is divided into two parts, comprising the switch mechanism proper between the lamp and battery, and an improved form of operating device mounted in the side of the case 35 for moving and locking the parts of the switch proper. More specifically, the invention consists in the features and details of construction which will be hereinafter more 40 fully set forth in the specification and claims.

In the drawings, in which similar numerals indicate the same parts throughout the several views, the invention is shown applied 45 to a pocket hand lamp of the ordinary cylindrical type, but obviously, it may be applied to such lamps of any cross-sectional area without departing from this invention.

Figure 1 is a central detail view partially 50 in section through a cylindrical hand lamp equipped with the device of this invention in its preferred form.

Fig. 2 is an enlarged detail view of the 55 essential parts of this invention, looking at the mechanism of Fig. 1 from the right.

Fig. 3 is a plan view taken on the line 3—3 of Fig. 1.

Fig. 4 is a perspective view of an improved form of switch operating mechanism, preferably used in connection with 60 the switch forming the principal feature of this invention.

Figs. 5 to 10 inclusive illustrate modified arrangements of the switch parts of this invention.

Fig. 11 is a sectional view in a modified form of the device, in which a fiber case instead of a metal case is used.

Fig. 12 is a perspective view of the metallic connector running lengthwise of the 70 case.

Fig. 13 is a plan view taken on the line 13, 13 of Fig. 11.

The pocket hand lamp shown in the drawing comprises a tubular metallic case 15 closed at its bottom end with a cap 16 and its upper end with a cap 18, perforated to allow the lens 20 to protrude in the usual manner. Immediately adjacent to and inside the lens 20 is the usual parabolic reflector 22 provided with an electric light bulb 24 whose outer terminal 26 is connected through the metal of the reflector 22 to the metallic case or shell 15, and thence through the spring 28 to the lower terminal of the 80 battery 30 contained within the lower portion of the lamp case 15. This construction includes means comprising a central terminal 32 of the electric light bulb and the upper terminal 34 of the battery 30 opposite 85 but separated from each other a substantial 90 distance, as shown.

In order to provide means for selectively detachably connecting these terminals 32 and 34 without it being possible for them to accidentally contact each other, an insulating plug or ring 36 is interposed between the two terminals 32 and 34. This ring is preferably made to fit the shell 15 so tightly that even though the lamp as a whole be dropped 100 in inverted position so that the lamp 20 strikes a hard resistance, the impact of the battery 30 cannot drive the ring 36 against the lamp bulb 24 and thus break it. The upper side of the insulating member 36 is 105 provided with a suitable electric conductor or switch member, preferably a strip of brass, 37, in contact with the central terminal 32 of lamp bulb 24, and suitably held in place with reference to the insulating mem- 110

ber 36, as for instance, by a rivet. The outer or free end 37^a of the brass strip 37 projects into a suitable perforation 40, extending vertically through the insulating member 36.

5 Similarly, the underside of insulating member 36 is provided with an electrical conductor or switch member, such for instance as brass strip 42, held in place by a screw 14, so that the strip contacts with 10 the upper terminal 34 of battery 30, the battery being held in this position by the spring 28, heretofore described. This conductor 42 has an L-shaped end 42^a extending up into the opening 40, heretofore described, in member 36. The parts of the 15 preferred form of the device shown in Fig. 1 are normally so positioned that the switch ends 37^a and 42^a do not contact with each other and consequently there is no current 20 flowing through the battery-lamp circuit, but obviously when switch ends 37 and 42 are brought together, the circuit will be completed through the electric light bulb and battery, with resulting illumination of the 25 lamp filament 46.

In order to move switch member 42, which is resilient material, from the position of Fig. 1 to a position wherein its end 42^a contacts with portion 37^a of switch member 37, 30 any sort of switch operating device may be employed, but it is preferred that the form shown in the drawings be used. The switch operating mechanism of this invention consists, in its preferred form, of a sliding bar 35 50 carrying at its upper end a block of insulating material 52. The bar proper is located, as shown, inside the case 15, but it is in fact continuous in one piece with the U-shaped spring member 54—56, lying out- 40 side the case 15, and terminating in the outwardly turned locking member 58, clearly appearing in Fig. 4. The juncture of parts 50 and 54, heretofore described, is cut away on opposite sides at 60 and 62 as shown, to 45 provide bearing surfaces at 60 and 62 against the side edges of a slot 64 formed lengthwise of the case 15. This slot 64 is of 50 such a length that the members 50, 54, and 56 can be moved backward and forward 55 longitudinally of case 15 sufficiently to cause switch member ends 37^a and 42^a to contact each other and release one from the other. This switch operating member just described is hand manipulated by the operator through 60 the agency of a rivet-head 66 projecting through an elongated slot 68 in a suitable cover plate or housing 70 attached to the case 15 by any suitable means, such as rivets. 65 This case or housing 70 is of peculiar 69 formation, in that it has stamped in its surface a recess 74 adapted to receive the locking end 58 of member 56. When the parts are in the position shown in Fig. 1, the switch operating mechanism is locked in position through the engagement of parts 58

and 74 and consequently the light switch cannot be closed until the operator has pressed upon member 66 and moved it inward against the spring action of members 54—56, which are of resilient material, a sufficient distance so that member 58 clears the inner surface of housing 70 and consequently the operator can move the operating device upward and thus force the contact member 42^a into engagement with member 37^a, thus completing the circuit in the manner described. 70

It will be noticed that owing to the fact that the case 15 forms a part of the return circuit between the electric light bulb and the battery, it is always necessary to insulate the switch operating member from the switch members themselves. In the preferred form of the device which is, as heretofore stated, accomplished by the use of 85 the insulating block 52 attached to the operating member 50, but this positioning of the insulating member is not at all essential, as will clearly appear from Figs. 5 to 10 inclusive, of the drawings. 90

In Fig. 5, upper and lower switch members 80 and 82 are provided contactable through the agency of an operating bar 84, insulated from 82 by a block of insulating material 86, secured to member 82 at 88. 95

Fig. 6 shows a modified form of the device in which upper and lower contact members 90 and 92 are provided, operable by a push member 96, carrying on its end an insulating block 98. In this form of construction, the device operates reversely to the mechanism of the preferred form in that the parts 96—98 and attached mechanism are employed to hold the contacts 90 and 92 normally out of contact with each other, while the spring action of member 92 moves them to closed circuit position, shown in Fig. 6, whenever members 96—98 are moved downward sufficiently to permit thereof. 100

Fig. 7 shows the same construction as in Fig. 6, except that the insulating block 100 is secured upon the underside of switch member 92 by a rivet 102, while the operating bar 104 carries no insulation. 105

Fig. 8 shows a construction identical with Fig. 5, except that an insulating block 106 is so attached to switch member 82 that the block extends downward therefrom instead of along the underside of switch member 82. 110

Fig. 9 shows a structure similar to Fig. 5, except that the upper switch member 108 is differently shaped. 115

Fig. 10 shows a modified form of construction showing upper and lower switch members 110 and 112 in which their respective ends engage each other through a plain flat contact instead of through a wiping engagement as in the other forms of device. 120

Obviously, the return contact between the 130

light bulb and battery may be made through a wire or metallic strip carried by a non-metallic case whenever the latter is employed.

5. Such a structure is shown in Figs. 11, 12 and 13, in which the case 15^a is made of fiber or some other non-metallic member and the electric connection between the metallic reflector 22 and the metallic bottom 16 of the case is made by a metallic strip 100 suitably inserted inside the fiber wall.

Having thus described my invention, what I claim as new and desire to secure by Letters Patent, is:—

15. 1. In a device of the class described, the combination of a suitable case containing a battery and an electric lamp, each having two terminals, means connecting one terminal of the battery with one terminal of the lamp, the other two remaining terminals being in proximity to each other, an insulating plate between the last mentioned terminals of the lamp and battery, switch members on opposite sides of said insulating plate contacting respectively the adjacent lamp and battery terminals, there being a recess formed in the insulating plate through which said switch members are movable into contact, and means operated from outside 20 the lamp case adapted to cause said switch members to operatively contact one with the other, for the purposes set forth.

2. In a device of the class described, a relatively long casing, a battery and an electric light bulb retained within the casing in general alinement one with the other so that one terminal of the light bulb is opposite one terminal of the battery, means electrically connecting the opposite terminals of the lamp and battery, an insulating member secured inside the case between the unconnected ends of the lamp bulb and battery adapted to prevent movement of the battery toward the lamp bulb, metallic 35 switch members on opposite sides of the insulating member so arranged as to be movable in a plane containing the longitudinal axis of the case into contact one with the other, and means operable from 40 outside the case for operatively connecting said switch members.

3. In a device of the class described, a lamp case, a dividing partition across the case, perforated in one portion, a pair of 45 switch members on opposite sides of the partition having their ends extending into the perforation in the partition and adapted to contact one with the other, and an operating member manipulatable from outside the case adapted to move one of the switch members with reference to the other.

4. In a device of the class described, a lamp case, a lamp and battery in the case, a 50 dividing partition across the case between

the lamp and battery perforated in one portion, a pair of switch members, one for the lamp, the other for the battery, on opposite sides of the partition having their ends extending into the perforation in the 70 partition and adapted to contact one with the other, and an operating member manipulatable from outside the case adapted to move one of the switch members with reference to the other.

5. In a device of the class described, a lamp case, a dividing partition across the case, perforated in one portion, a pair of switch members on opposite sides of the partition having their ends extending into 80 the perforation in the partition and adapted to contact one with the other, an operating member manipulatable from outside the case adapted to move one of the switch members with reference to the other, and 85 insulating means interposed between the operating member and the switch member which it moves, for the purposes set forth.

6. In a device of the class described, a metallic case, an electric battery occupying one end of the case and having one terminal connected thereto, an electric light bulb occupying the other end of the case and having one terminal connected thereto, switch contact members movable into and 90 out of contact with each other normally insulated from each other, interposed between the lamp bulb and the battery so as to permanently contact respectively with one terminal of the lamp and one terminal 95 of the battery, means operated from outside the case for operatively contacting said switch members, and an insulating device between said operating member and the switch member, for the purposes set forth.

7. In a device of the class described, the combination with a battery case, a housing upon the outside of the case, separated therefrom, a switch operating member consisting of a bar movable inside the case 110 lengthwise thereof, integrally connected to a spring member correspondingly movable inside the housing between the housing and case, means operable from outside the housing for reciprocating the spring member in the housing and compressing the spring, and a member on the spring entering a depression on the housing, releasable therefrom when the spring is compressed, 115 for the purposes set forth.

8. In a device of the class described, the combination with a battery case, a housing upon the outside of the case, separated therefrom, a switch operating member consisting of a bar movable inside the case 120 lengthwise thereof, integrally connected to a spring member correspondingly movable inside the housing between the housing and case, means operable from outside the housing for compressing the spring and a 130

member on the spring entering a depression on the housing, releasable therefrom when the spring is compressed, for the purposes set forth.

- 5 9. A device of the class described, the combination of a case, a switch operating member comprising a Z-shaped piece of spring metal 50—54—56, cut away on opposite sides at one bend of the Z as at 60 and 10 62 so as to permit sliding of the member in a slot formed in the case with one bar of the Z inside the case and the remainder outside thereof; a housing 70 attached to

the outside of the case and inclosing the portions of the operating member, which 15 are outside the case, and means operatable from outside the housing for compressing the operating member and for reciprocating said operating member.

In witness whereof, I have hereunto subscribed my name in the presence of two witnesses.

JOSEPH C. FORD.
